Primary Examiner — Stacia Cadmus*(74) Attorney, Agent, or Firm* — Wood Herron & Evans LLP(57) CLAIM

The ornamental design for a wheel, as shown and described.

DESCRIPTION

FIG. 1 is a front left perspective view of a wheel according to the present invention.

FIG. 2 is a front view of the wheel shown in FIG. 1.

FIG. 3 is a left side view thereof.

FIG. 4 is a front left perspective view of a wheel according to a second embodiment of the present invention.

FIG. 5 is a front view of the wheel shown in FIG. 4; and,

FIG. 6 is a left side view thereof.

The broken line showing of the rear of the rim, the valve stem hole, the bolt holes and the center hole in the central hub area is included for the purpose of illustrating environment and forms no part of the claimed design.
